UNITED STATES PATENT OFFICE

HERMAN A. THIERRY, OF DETROIT, MICHIGAN

FLOOR PAD

Application filed November 29, 1929. Serial No. 410,384.

This invention relates to a floor pad and has to do particularly with a pad which affords a degree of resiliency yet one which will not hold or confine dirt or dust, and which is of a construction that will not unduly mar or soil articles which come in contact with it.

The invention is concerned particularly with a mat which is useful in a pit at the end 10 of a bowling alley. Of course, the invention is not limited to a mat to be used in this location only, as the construction may be employed in any place desired as for example, runners behind counters, or fountains, or used 15 adjacent machines or the like.

In order that the advantages of the mat may be better understood, it will be described with respect to the requirements of a mat 20 in a bowling alley pit. The pins and the balls, which are relatively heavy, strike the floor of the pit with considerable impact and of course some sort of a mat or pad is necessary to preserve the pins and balls, and also to preserve the floor which would become splintered and in turn further damage the pins and balls. A rubber mat has been used but this is undesirable because a pin which slides 25 across it receives a mark. Furthermore, particles of dust and grit readily collect and this 30 grinds into the wooden pins and balls. Mats of fabric construction such as inter-woven strands of rope-like material or the like or cocoa mats have been used, but they not only wear out quickly but also collect the dust and 35 grit which in turn soils the pin which is undesirable and results in that the pin has to be cleaned and re-finished at short intervals of time.

The present invention contemplates a mat 40 construction which comprises generally spaced strips of relatively flexible material which are supported by resilient elements. The mat accordingly is more or less of an open work construction which will afford the 45 desired resiliency but which will permit particles of dirt and grit to pass through.

In the accompanying drawings:

Fig. 1 is a plan view of a mat constructed in accordance with the invention.

Fig. 2 is a perspective view of a portion of

a mat having a part cut away to show the construction.

The mat is made up of a plurality of relatively long strips of material which are disposed in spaced relation and which preferably are parallel. These strips may be of different materials depending upon the requirements of the use to which a particular mat is to be used. Cushioning devices support these strips and these devices essentially 55 are relatively long lengths of a material of a resilient nature disposed in spaced relation and extending cross-wise or substantially cross-wise of the first mentioned strips. Ordinarily the two sets of strips will be disposed at right angles to each other. The two sets of strips are adjoined preferably at each point of crossing.

The specific structure will be appreciated by reference to the drawings wherein strips 1 are shown, and it will be noted that the mat comprises a plurality of these strips disposed in spaced manner. The resilient supporting elements are preferably of rubber. These elements are also preferably in the 70 form of long lengths or strips and are disposed at right angles, preferably, to the strips 1. They are illustrated at 2. An advantageous form for the supporting strips is that of a curved or substantially semi-circular or U-shape in cross section. The legs of the U as illustrated at 3 and 4 are designed to contact with the supporting floor while the upper-most strips are connected to the supporting strips substantially at the right 75 portion thereof. The strips may be secured together by one or more rivets 5.

When a mat of this construction is to be used for example in a pit at the end of a 80 bowling alley, it is preferable that the strips 1 be of fiber. Strips which are approximately 1½ inches wide by $\frac{1}{16}$ of an inch in thickness have been found quite satisfactory. The mat protects the floor but due to its open construction allows all dirt and grit, etc., to 85 pass through onto the supporting floor. Accordingly the pins do not become soiled as readily as they do with a mat which collects and retains the dirt. Moreover objectional 90 marks are not placed on the pins as they slide 95

over the fiber strips. The fiber strips are relatively strong so that there is no breakage in the event of a pin or ball striking heavily on a strip between two supporting members.

5 The semi-circular or U-shaped formation of the supporting elements render considerable resiliency to the mat as weight applied thereto causes the legs of the U-portion to bend with the bight portion of the U moving downwardly, and, in a way flattening out the U. The construction is nicely adapted for use as runners or the like where persons are standing or walking. In this event the strips 10 may be of wood in place of fiber although fiber is preferred for the bowling alley pit 15 because it is not so liable to break and splinter under impact of pins or balls.

Obviously, the mat can be made up in any desired size, and for example may be long 20 and narrow in the event the mat is to be used as a runner behind a counter or the like. The fiber or other strips may run lengthwise or cross-wise as regards the length of the mat although it is thought to be preferred that 25 they run lengthwise. The semi-circular shaped supporting elements may be of solid rubber formation while also they may have one or more layers of fabric embedded in the rubber. Supporting elements having a 30 curvature based on an interior diameter of about $\frac{1}{8}$ of an inch have been found to give satisfactory results. This of course may vary. The supporting strips, while advantageously are of U-shape in cross section, 35 may be constructed of different forms. When the U-shape is used the ends of the legs of the U frictionally grip the floor so that when weight is on the mat the bight portion is bent downwardly but the legs are 40 not spread apart at the floor in any appreciable degree. However, the resilient supporting elements may be of tubular formation or solid blocks of rubber or the like.

Claims:

45 1. A floor mat comprising a plurality of separate spaced strips, a plurality of separate resilient supporting elements substantially semi-circular in cross section disposed in spaced relation and extending at substantially 50 right angles to the strips, the strips and supporting elements being secured together at the points of crossing, said supporting elements flexing transversely under load and being spaced apart sufficiently to permit of 55 independent flexing of each element.

2. A floor mat comprising a plurality of spaced strips, a plurality of spaced supporting elements disposed substantially at right angles to the strips, said supporting elements 60 being formed of flexible material and substantially U-shaped in cross section, said supporting strips being positioned so that the U is inverted and being secured at their bight portions to the said strips at the point of 65 crossing and with the ends of their legs

adapted to contact with a floor, said legs being adapted to spread under load and the said elements being spaced apart sufficiently to permit of free and independent spreading of the legs of each element.

3. A floor mat comprising a plurality of spaced strips disposed substantially parallel, a plurality of rubber supporting elements substantially U-shaped in cross section disposed in widely spaced relation as regards 75 their cross sectional dimension and substantially at right angles to the strips and with the U inverted so that the ends of the legs are adapted to contact with the floor, and means connecting the strips and supporting elements at the points where the strips and elements cross.

4. A floor mat comprising a plurality of spaced strips disposed substantially parallel, a plurality of rubber supporting elements 85 substantially U-shaped in cross section disposed in relatively widely spaced relation whereby each element is entirely independent of the other and substantially at right angles to the strip and with the U inverted, and 90 means connecting the strips and supporting elements at the points where the strips and elements cross, said means connecting the strips to the bight portion of the inverted U so that the weight on the mat tends to flatten 95 the U.

5. A floor mat comprising a plurality of fiber strips disposed in spaced and substantially parallel manner, a plurality of rubber supporting elements of strip like form disposed in relatively widely spaced substantially parallel manner and at substantially right angles to the strips, the spacing being such that each element is entirely free of interference from the other elements, said 100 supporting members being substantially U-shaped in cross section and disposed with the U inverted whereby the legs of the U are adapted to contact with the floor, and means connecting the strips to the bight portions 110 of the supporting elements.

In testimony whereof I affix my signature.
HERMAN A. THIERRY.
